Fig. 5.

To all whom it may concern:

Be it known that we, Robert Goldman and Roy R. Nemzer, both citizens of the United States and residents of South Hempstead, in the county of Nassau, State of New York, having invented a new, original, and ornamental Design for a Child's Toy Chest, of which the following is a specification, reference being had to the accompanying drawing, forming a part thereof, and of which

Fig. 1 is a top plan view of a child's toy chest showing our new design.

Fig. 2 is a right side elevational view thereof.

Fig. 3 is a rear elevational view thereof.

Fig. 4 is a front elevational view thereof, and

Fig. 5 is a right side elevational view similar to Fig. 2 with the roll cover in open position.

We claim:

The ornamental design for a child's toy chest, as shown.
